(57) **CLAIM**

The ornamental design for an eye patch, as shown and described.

DESCRIPTION

FIG. 1 is a front elevational view of an eye patch showing my new design;

FIG. 2 is a left side view thereof;

FIG. 3 is a right side view thereof;

FIG. 4 is a rear elevational view thereof;

FIG. 5 is a top plan view thereof, and,

FIG. 6 is a bottom plan view thereof.

Dashed lines in the body of the article represent thread stitches.

The broken lines at the strap portions in FIGS. 1–6 represent indeterminate length.
